When solenoid E is energized and chain 54 moved to turn sprocket 55, switch arm 58, which is a spring, rides up the forwardly inclined surface 60 of switch plate 61, and 5 then, under spring tension, contacts with the surface 61, closing a circuit through the lamp N for illuminating the person or object to be photographed. The movement of arm 58 to the left from its position shown 10 in Figure 1 is very rapid. At the end of its movement to the left it, being sprung, passes the end of the contact plate 61 and moves backward onto a second plate 62 on which plate it reverses its action and moves 15 to the right due to the action of weight 56.

The movement of the arm 58 to the right is slow because of the action of the dash-pot 57 in retarding the downward movement of the weight. At the time arm 58 moves backward upon contact plate 62, contact arm 59 comes into contact with a contact plate 63* and closes the circuit leading to motor 2. In the movement to the right of arm 58 of plate 62 the lamp N continues to remain illuminated and arm 59 remains on plate 63* for sufficient time to enable such rotation of motor 2 as to rotate the cam 63 to such position that lever 64, arm 65 and weight 66 are lifted upwardly to cause the contact end of 30 arm 64 to engage a contact plate 67 which serves to continue the circuit through the drive motor.

As the cam continues to rotate, arm 64 is permitted to fall. Dash-pot 68 acting 35 upon check-weight 69 serves to check the downward movement of the arm so that the arm does not leave contact 67 until the last exposure of the film whereupon the arm does leave contact 67 and the motor 2 stops. A second contact 67* is disposed in such position that its active face is not struck by arm 64 in its upward movement, but is struck by the arm in its downward movement. The contact of arm 64 with contact 45 plate 67* closes a circuit through the solenoid 12 for effecting the cutting operation during the rotation of the cam, a member C mounted thereon momentarily closes contacts A, A*, and closes a circuit through magnet 50 P, permitting the flow of liquid to the tank D through tubes from a supply tank R, one of the tubes being indicated at 74.

If, prior to the cutting operation upon an exposed strip of film, a previously exposed 55 film passes through the machine in completed form, and the timing mechanism shuts off the driving motor M, this will not affect the proper treatment of said exposed strip of film because the feeding and controlling means up to and including the cutting operation is independent of the feeding and controlling mechanism for the film subsequent to the cutting operation, and the movement of the elements in the cutting operation is employed to throw into action the

second named means. Thus the motor M being motionless, film is fed through the camera in accordance with the timing of cam 63 and its associated parts until arm 64 leaves the camera motor contact 67 and 70 shuts off current to the feed motor 2, the arm 64 continuing its dropping movement until it closes the circuit through contact 67* and the solenoid 12 for performing the cutting operation. In the cutting operation 75 rod 11* connected to the solenoid armature bridges contacts 38 and through the connections hereinbefore described starts the driving motor M and the timing control therefor.

If the second or succeeding exposed strips of film follow a previously exposed strip into the tank D and thus while the first strip is being developed and finished in said tank, the completion of the first strip and its discharge from the tank will not stop the tank feeding mechanism and the latter will remain in action until the last strip is fed through the tank for the reasons now to be described.

Assume an exposed strip of film to be half way through the tank D, so that in ordinary course the motor M has performed its function for half the time period between its starting and stopping by the control mechanism. As an example, take the time of feeding through the tank to be four minutes and the feeding to be half completed, leaving a period of two minutes for the reduction gearing and connections with shaft 25 to carry blade 46 up incline 46* until it snaps over upon contact 49 to energize magnets 36, 37, and thus release arm 24 so that it will spring up to separate the contacts 28 in the circuit for motor M. Now assume that a coin is placed in the machine and the feeding mechanism of the film is started, this feeding mechanism continuing in action until the predetermined number of exposures have been made upon a strip and the strip is severed by knife 7. In the action of solenoid 12 to operate knife 7, rod 11* will be moved downwardly to operate pawl 23. But arm 24 will be below the range of pawl 23 so that the downward movement of the pawl will be inactive. However, contact 39 will instantly bridge the contacts 38, and solenoid 36, 37 will be energized thus releasing the friction disks and permitting spring 27 to move switch arm 24 toward the contacts 28 in the circuit for motor M. However, these contacts will not be separated, because pawl 23 will lie in such position as to stop the complete movement of switch arm 24. In other words, switch arm 24 will move back to exactly the position where it is customarily moved by pawl 23 in separating the insulating knife 27, carried by the switch arm, from the contacts 28. Therefore, driving motor M will

UNITED STATES PATENT OFFICE.

JOSEPH KAHLER, OF NEW ALBANY, INDIANA, ASSIGNOR, BY DIRECT AND MESNE ASSIGNMENTS, OF ONE-HALF TO GOHMANN BROS. AND KAHLER COMPANY, OF NEW ALBANY, INDIANA, A CORPORATION OF INDIANA, AND ONE-HALF TO VICTOR E. SCHMIEDEKNECHT, OF LOUISVILLE, KENTUCKY.

SAND BAFFLE.

Application filed November 21, 1925. Serial No. 70,528.

My invention relates to baffles and more particularly to a sand baffle for sandslinging machines.

The object of my invention is to provide simple, efficient, durable, economical and easily operated means for retarding the force of the sand discharged from sand-slinging machines into a flask or mold, whereby the initial layer of sand is smoothly, evenly and unbrokenly distributed over the casting pattern so as to prevent creeping of the sand or the formation of cracks therein upon its surface adjacent the pattern, thereby strengthening the sand mold and eliminating roughness of its surface, in order to insure substantially perfect and smooth castings, as well as to reduce the usual loss by reason of defective castings, caused by failure to regulate the flow of sand discharged into the mold.

Another object of my invention is to produce means whereby the amount of wear upon the patterns, caused by the force with which the molding sand is thrown and packed into the flask is reduced to a minimum.

My invention consists in providing an adjustable baffle for the impeller head of sand-slinging machines.

My invention also consists in the construction, combination, location and arrangement of parts, as herein set forth and claimed.

In the drawings:

Fig. 1 is a side elevation of one form of baffle to be mounted beneath the head of a sandslinging machine with the baffle shown in an open or non-operating position;

Fig. 2 is a plan view thereof;

Fig. 3 is a perspective view of Fig. 1 partly broken away to show the baffle plate which is shown in closed or operating position.

Fig. 4 is an end elevation of Fig. 1;

Fig. 5 is a vertical section of the impeller head of a sandslinging machine with my invention applied thereto in operative position and a vertical section of the flask and match board directly beneath; and

Fig. 6 is a similar view with my invention shown in the open or inoperative position.

In the embodiment of my invention, as illustrated, and which shows a preferred construction, I provide a baffle composed of

frame 1 which comprises ends 2 and 3 and sides 4 and 5, respectively. The sides 4 and 5 have grooves 6 and 7 within which baffle plate 8 is slidably received. The baffle plate 8 has a plurality of slots 9 spaced apart from each other to form sand retarding and deflecting cross bars or webs 10 and positioned between sides 11 and 12 of said baffle plate 80 and is provided with manually operative handle 13. The baffle plate 8 is provided with removable stops 14 and 15 and fixed stops 16 and 17, respectively, to limit its longitudinal movements. End 3 of frame 1 has notches 18 and 19. To insert the baffle plate 8 within grooves 6 and 7 of sides 4 and 5, respectively, remove stops 14 and 15 and insert end 20 of handle 13 into said grooves through end 3 of frame 1, stops 16 and 17 passing through notches 18 and 19, respectively. Then slide the baffle plate 8 within the grooves 6 and 7 until the faces 21 and 22 of stops 16 and 17 abut or contact the inside face 23 of end 2, as shown in Fig. 2. Then insert stops 14 and 15. By this construction the baffle plate 8 is free to be moved longitudinally within grooves 6 and 7, its outward movement, as indicated by arrow 24 and shown in Figs. 1, 2 and 6, being limited by stops 16 and 17 coming in contact with face 23 of end 2. The inner movement (which will be hereinafter termed as the "closed position") as indicated by arrow 25 and shown in Figs. 3 and 5, is limited by stops 14 and 15 contacting the outside face 26 of end 2. Ends 2 and 3 of frame 1 are provided with holes 27 which register with holes 28 in the lower end 29 of impeller head 30 which is a part of the present and well known sandslinging machines (not shown). For purposes of illustration I have shown in Fig. 5 my baffle attached to the impeller head 30 by stud bolts 31 and with the baffle plate 8 shown in closed or operative position. Directly beneath this I have shown a flask, comprising cope 32, match-board 33 and drag 34. In Fig. 6 I have shown the same elements but with the baffle plate 8 withdrawn to inoperative position.

To describe the operation of my invention, it will be assumed that the match-board 33, having pattern 33^a fixed thereon, is properly fixed or held between the cope 32 and drag

34 and is placed beneath the impeller head 30 ready to receive sand 36 which is delivered to said impeller head 30 by conveyor belt 37 and picked up by cup-shaped blade 5 38 which rotates in the direction of arrow 39. When the cup-shaped blade 38 is in the position shown in Figs. 5 and 6 the charge of sand 40, previously held therein, is thrown with great force upon baffle plate 8, which is 10 in the closed position. The bars 10 of baffle plate 8 break the force of the sand 40 and deflect it through opening 9, as shown at 41 and causes it to fall mildly and softly, thereby allowing a layer of loosely packed 15 sand 42 to smoothly and evenly cover the pattern 33^a. After said layer of loosely packed sand covers the pattern 33^a the baffle plate 8 is manually withdrawn to inoperative position, as shown in Figs. 1-2 and 6, 20 inclusive, thereby allowing the force of sand 40 to evenly pack or tamp the first layer of loosely packed sand 42, as shown in Fig. 6.

With this method of packing and tamping the mold the objection of rough castings is 25 overcome. Heretofore a serious objection to sand-slinging machines, as now built, is, that the sand is thrown with the same force continually during the operation of filling and packing the flask with sand. This is 30 not only injurious to the patterns but also causes the first application or layer of sand to skid or creep, which results in cracks and uneven surfaces in the sand mold, causing 35 rough castings. It is readily seen that these objections are eliminated by the use of my novel baffle.

While I have shown and described the baffle plate as adapted and intended for a particular type of machine, it may also be used 40 in any other situation to which it is adapted and while I have shown a particular construction, it will be understood that it may be varied in construction and arrangement such as may be necessary for its use in combination with sand machines in this class, 45 and may also be differently mounted relative to the sand-slinging machine, without

departing from the scope or spirit thereof, as defined in the claims.

What I claim as new and desire to secure 50 by Letters Patent is:

1. In combination with a sand-slinging machine having an impeller head, a baffle comprising a frame attached to said head, and a manually operative baffle plate adapted 55 to slide within said frame.

2. In combination with a sand-slinging machine having an impeller head, a baffle comprising a frame having grooves therein, said frame being located beneath said head, 60 a manually operative baffle plate adapted to slide within said grooves, stops on said baffle plate adapted to engage said frame, and a plurality of openings in said baffle plate.

3. In combination with a sand-slinging 65 machine having an impeller head, a manually operative baffle attached to said head and adapted to slide relative thereto, for the purposes set forth.

4. In combination with a sand-slinging 70 machine having an impeller head, a manually operative baffle mounted below the sand discharge outlet thereof and adapted to be moved relative thereto.

5. In combination with a sand-slinging machine having an impeller head, a baffle comprising a frame attached to said head, and a manually operative baffle plate adapted to 75 slide relative to said frame.

6. In combination with a sand-slinging 80 machine, a baffle having a handle and provided with a web or series of spaced apart bars, means for moving said baffle relative to the sand discharge outlet of said sand-slinging machine whereby when the baffle is in closed position the force of the sand is broken, causing the sand to be deflected and discharged upon the pattern mildly and evenly and whereby when the baffle is withdrawn to open position the remainder of the sand is permitted to be forcibly discharged 85 whereby it is properly packed in the mold. 90

JOSEPH KAHLER.
